UNITED STATES PATENT OFFICE.

HARRY A. MARRABLE, OF HOBOKEN, NEW JERSEY.

COPYHOLDER.

Application filed April 11, 1927. Serial No. 182,815.

This invention relates to a copy holder for typewriters and the like, the general object of the invention being to provide means for holding the copy directly in front of the operator so that the operator can keep his eyes straight ahead in reading the copy, thus eliminating the necessity of the operator turning his head to read copy placed on his desk at one side of the typewriter which causes him to assume an unnatural attitude and thus not only injures the eyes but also the neck and other portions of the body.

5

A further object of the invention is to provide a casing having a platen therein 15 which presses the copy sheet against a portion of the casing so that the sheet will be fed as the roller is turned, the roller having a flat portion which will permit manipulation of the paper when said flat portion is 20 brought opposite that portion of the casing against which the sheet is pressed by the round part of the roller.

A still further object of the invention is to provide means whereby the device can be 25 easily attached to a typewriter or the like.

This invention also consists in certain other features of construction and in the combination and arrangement of the several parts, to be hereinafter fully described, illustrated in the accompanying drawings and 30 specifically pointed out in the appended claim.

In describing my invention in detail, reference will be had to the accompanying drawings 35 wherein like characters denote like or corresponding parts throughout the several views, and in which:—

Figure 1 is a side view of a typewriter showing the invention in use thereon.

40 Figure 2 is a front view of the invention with a portion of the device in section.

Figure 3 is a perspective view of the device.

45 Figure 4 is a perspective view of the platen or roller thereof.

Figure 5 is a transverse sectional view through the device.

Figure 6 is a sectional view through one end of the device.

50 In these views 1 indicates the casing which has its top and rear open and has its front provided with a long window forming slot 2. A bracket 3 is secured to each end of the casing and these brackets are adapted 55 to be secured to the rear part of the type-

writer or the like in any desired manner, such as by the clips 4 secured to the ends of the brackets and fastened to the rear corners of the typewriter by the screws 5. A platen or roller 6 is rotatably mounted in 60 the casing through means of the pins 7 which pass through holes in the ends of the casing and are held in sockets in the ends of the roller by the screws 8, the outer ends of the pins carrying the knobs 9. The roller 65 is provided with a flat part 10.

As will be seen the casing is held at the rear of the typewriter above the carriage so that the operator can see the copy sheet through the window without turning his 70 head. The copy sheet is pressed by the roller against the bottom of the casing so that as the roller is turned the sheet will be fed through the casing so as to bring new portions of the sheet in front of the window. 75 When the flat portion of the roller comes opposite the bottom of the casing pressure on the sheet is relieved so that the sheet can be moved to properly place it in the device with the lines of copy thereon in proper position 80 at the window.

With this invention the typist can readily read the copy without turning his head, thus relieving strain both on the eyes and on the neck and by simply turning one of the rollers 85 the copy sheet can be fed through the device, the flat portion of the roller enabling the copy sheet to be adjusted in the casing. The window is preferably made of such a size as to make three lines of copy visible therethrough. 90 This device also enables the typist to readily pick up the point where he left off in changing the sheets in the typewriter or whenever he has stopped writing and there is no danger of losing the copy sheet as there is when 95 it is placed on the desk.

I also provide means whereby the platen or roller 6 can be given a step by step movement by ratchet mechanism operated by a key which is located adjacent the keyboard of the 100 typewriter. This arrangement comprises a lever 11 pivoted to one side of the typewriter, as shown in Figure 1, with a key 12 at its front end and its rear end pivoted to a link 13 which has its upper end pivoted to an arm 14 which is pivoted to one of the pintles 7 of the roller, on which pintle is placed a ratchet wheel 15 which is engaged by a dog 16 carried by the arm 14. The rear end of the lever 11 works between two stop pins 17 105 110

and a spring 18 normally holds the lever against the lower pin. Thus by depressing the key 12, the lever will be moved to actuate the ratchet mechanism to feed the platen one 5 step forward. As pressure is removed from the key, the spring 18 returns the parts to normal position so that when it is again depressed, the parts will be moved to again give the platen a forward movement.

10 It is thought from the foregoing description that the advantages and novel features of my invention will be readily apparent.

I desire it to be understood that I may make changes in the construction and in the 15 combination and arrangement of the several parts, provided that such changes fall within the scope of the appended claim.

What I claim is:—

A copy holder of the class described com-

prising an elongated casing having its ends, 20 bottom and front closed and its top and rear open, with an elongated slot in its front forming a window, a roller in the casing having a flat portion, pintles passing through the ends of the casing into the ends of the roller, 25 screws passing through the ends of the flat portion of the roller and engaging the pintles for holding the same in place, a knob on the outer end of each pintle, whereby the roller can be rotated, the roller acting to grip a sheet of paper between itself and the bottom of the casing whereby when the roller is turned, the sheet will be fed past the window, the flat portion acting to release the sheet so that it can be adjusted by hand and supporting members attached to the ends of the casing and having clips at their lower ends. 30 35

HARRY A. MARRABLE.
